The ornamental design for an electronic device, as shown and described.

DESCRIPTION

FIG. 1 is a bottom front perspective view of an electronic device showing our new design;

FIG. 2 is a front view thereof;

FIG. 3 is a rear view thereof;

FIG. 4 is a top view thereof;

FIG. 5 is a bottom view thereof;

FIG. 6 is a left view thereof;

FIG. 7 is a right view thereof; and,

FIG. 8 is an enlarged cross-sectional view taken along the line 8-8 of FIG. 2.

The broken lines in the Figures show portions of the electronic device that form no part of the claimed design. The dot-dash lines in the Figures show boundaries that form no part of the claimed design.

The shade lines in the Figures show contour and not surface ornamentation.
